UNITED STATES PATENT OFFICE.

GEORGE C. ADAMS, OF SAN FRANCISCO, CALIFORNIA.

OIL-BURNING FURNACE.

Application filed October 8, 1921. Serial No. 506,507.

To all whom it may concern:

Be it known that I, GEORGE C. ADAMS, a citizen of the United States, residing at San Francisco, in the county of San Francisco and State of California, have invented new and useful Improvements in Oil-Burning Furnaces, of which the following is a specification.

The present invention relates to improvements in furnace construction for oil burning boiler furnaces of the type exemplified in my U. S. Letters Patent No. 1,382,402, issued June 21, 1921.

An object of the present invention is to improve the construction of an oil burning furnace so as to provide for better combustion and greater heat at a relatively low fuel consumption; to provide a steady flame whether large or small; to eliminate smoke and noise and to permit of an effective control of the flame, at all times.

Another object of the invention is to provide novel means for introducing air as a supporter of combustion in such manner that effective combustion takes place, there being provided beneath the floor of the furnace an air chamber together with means for heating the air within said chamber and conducting the same to a specially constructed air intake arrangement which latter is located beneath the burner and forwardly thereof.

A further object is to provide improved furnace construction for furnaces having a plurality of independent oil burners, there being special construction to separate the portions of the furnace required for the successful operation of each burner so that when only one burner is under operation the operation of said burner will not be effected by the other constructions for the burner or burners not in operation.

The invention further consists of a peculiar combination, association and inter-relation of specially constructed parts or elements as will be hereinafter more fully described.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my

invention, but it is to be understood that I do not limit myself to such form since the invention as expressed in the claims may be embodied in a plurality of forms.

60

Referring to the drawings:

Fig. 1 is a fragmentary longitudinal sectional view showing the furnace constructed in accordance with the present invention.

Fig. 2 is a top plan view of the furnace 65 shown in Fig. 1.

Fig. 3 is a sectional view taken on line 3—3 of Fig. 2.

Fig. 4 is a fragmentary vertical sectional view showing the arrangement of the air 70 conducting pipes at the intake ends thereof.

Fig. 5 is a cross sectional view taken on line 5—5 of Fig. 1.

Fig. 6 is a similar cross sectional view taken on line 6—6 of Fig. 1; Fig. 7 is an enlarged fragmentary vertical sectional view 75 of a modified form of furnace construction wherein the deflector wall or member is located at the back of the furnace, which latter is formed with an air intake opening.

Fig. 8 is a fragmentary vertical sectional view taken on line 8—8 of Fig. 2.

Fig. 9 is a perspective view of the deflector wall.

Fig. 10 is a fragmentary longitudinal sectional view taken on line 10—10 of Fig. 2.

In carrying out the present invention the floor of the furnace is inclined slightly from a point beneath the burner, in steps or stages to a mediate portion of the floor and at certain points of the inclined floor, a plurality of upwardly diverging, relatively large air inlet openings are formed. The burners project the flame over the inclined steps of the floor in a substantially horizontal direction and in such manner that the flames pass over the air inlet openings, said flames are spaced above the openings sufficiently to permit the air to readily expand and heat and to mix with the fuel gases burning in the 100 furnace. The spacing of the flames prevents smothering of the openings, permits of a better combustion with a resultant saving in fuel, and maximum heat production. In the ordinary air burning furnace for boilers, the 105

flame usually passes directly over small parallel sided air intake openings formed in a level furnace floor and this tends to smother the ports or openings so that an insufficient quantity of air is admitted and combustion 110 is not properly supported. Furnaces of this type are difficult to manage under a small

flame and when overloaded make an objectionable noise. The above features are characteristic of my previous Patent No. 1,382,402. In the present invention I enhance the advantages exemplified in my prior patent by a special furnace construction wherein an air chamber, preferably extending the length of the furnace, is formed beneath the floor so that the air confined beneath the floor will be heated by radiation of the fire-brick forming the floor wall. Instead of employing the ordinary bars or girders to support the fire-brick constituting the floor, I employ a plurality of pipes or conduits which extend longitudinally of the furnace and are open at both ends, said pipes serving the double function of supporting the floor and conducting heated air from the space beneath the floor to a point where it will readily pass upwardly thru the intake openings and into the furnace. The pipes are arranged in such manner that they are readily heated and air thus passing thru the pipes will be more effectively and quickly heated for this reason. The invention contemplates other special construction, as to the furnace, which tends to provide an effective draft of air from the chamber beneath the floor so that when said air passes thru the several intake openings and around the flames it is effectively heated and will readily support combustion. In addition the construction of the furnace of this invention is specially provided for increasing the efficiency of multi-burner furnaces, the arrangement being such that when only one burner is operated, the flame from said burner will not be ill-affected by the air currents taken in from the air intake openings for the burner or burners not in operation.

Referring to the drawings, 1 designates a furnace having front and rear end walls 2 and 3, and side walls 3', the front wall 2 being provided with the usual opening 4 having draft regulating doors 5. In this particular type of furnace, I employ two burners 6 and 7, both of which project horizontally into the furnace, thru openings 8 at points above the openings 4. The floor 9 of the furnace is formed of fire-brick and is supported above the ground or floor level, upon a plurality of closely associated but slightly spaced, longitudinal pipes 10, which pipes extend for the length of the floor and are in turn supported on transverse supporting pipes 11. The floor is thus supported so as to provide beneath the same, an air space or chamber A, extending from one end wall to the other. The floor is inclined from a point beneath the burner to a point intermediate of its ends, at which latter there are formed depressions or firepits 12, which produce a swirling effect, with the result that the air is thoroughly mixed with the gases and a thorough combustion follows. This also retards

movement of the flame and intensifies the heat throughout the furnace.

Beginning at points beneath the burners, the floor inclines in the first stage or steps 13, which steps 13 are supported by pipes 14 extending transversely in the furnace. These portions 13 are, for example, two feet wide and terminate forwardly, for example, a little over twelve inches in front of the burner. At points along the outer sides of the portions 13, and below the inclined surfaces thereof there are provided air ports 15 communicating with the air chamber A. In front of these openings and on opposite sides of the portions 13 are several layers of fire brick 16, over which air passes from said ports into the furnace and around the burner. On top of the portions 13 of the floor, on each side of the burner, are baffle members 17, diverged forwardly. Air introduced thru the ports 15 will pass between these baffles and the burner and around the sides and in front of said baffles and when said baffles become heated, they will heat the air thus passing in close proximity thereto. By diverging the baffles, the fuel gases will be prevented from being smothered by too great a rush of air from behind the burner whereby a small flame may be effectively fired and maintained, intense and steady. The floor preferably has extra walls 18 and 19 extended on opposite sides of the main side walls of the furnace interiorly thereof, for a short distance and a longitudinal partition wall 19' extends between the floor and ground level so as to separate the chamber A. The walls 18 and 19 are to be formed of fire-brick and are arranged so that the spaces on the sides of the burners will be the same whereby the control of the burners may be effected with ease and accuracy. Where a plurality of burners are used, in order to equally divide the space therebetween, I employ a vertical partition wall 20 which extends from the end wall 2 at a point forwardly of the step 13, a distance beyond said step 13, for example, two feet in advance thereof. The height of this wall is such that it extends about one foot above the burner so as to form a complete partition between the burners. A lower wall extension 21 extends from the forward end of the wall 20 to the far side of the firepit 12 and serves to prevent a draft of air or fuel gases from one burner from entering the region around the other burner. These walls provide for an effective control of the flames from the burner and prevent currents or eddies around the burners such as would deflect the flames.

The second step 22 of the inclined floor begins from a point preferably one-half inch below the lower end of the first step and consists of transverse rows of fire-brick, which provides a plurality of transverse air

intake openings 23. The sides of the bricks of each row are beveled so as to provide upwardly enlarging ports or openings between the rows. The bricks are supported by pipes 24 and are inclined downwardly and forwardly but at a less inclination than the first stage. The floor on opposite sides of this stage is closed and solidly formed as in the ordinary furnace. Rows of fire-brick 25 are placed on the sides of the stages 22 and extend a slight distance above the tops of the rows of the fire-brick of each of which said stages are formed so as to confine the intake or air to the region immediately over the openings and under the flames.

The third stage 26 is not inclined and is disposed about three inches below the lower end of the second stage, with its forward edge defining the upper edge of the firepits. 20 These steps extend entirely across the width of the furnace and the remaining portion of the floor likewise extends across from one side wall to the other and is solidly formed in the customary manner.

25 In order to provide for maximum intake of air for supporting combustion, the sides of layers 16 of the fire-brick, at their forward edges on opposite sides of the stage 13 are chamfered or bevelled as at 27 so as to 30 provide inclined passages or ports 28 on opposite sides of the stages 13. These passages cause air to be drawn upwardly at an inclination to the vertical and around the tops of the air intake openings at the forward 35 ends of the second stages. This provides for intaking of air at points on the side of the flame in such manner that the air is permitted to expand beneath the flames and has no tendency to force or deflect the flames 40 upwardly.

In order to provide for an effective and even distribution of air drawn in thru the openings 4 at the forward ends of the chambers A, there are provided baffle walls 29 at 45 the forward ends of the said chambers. These baffle walls are spaced about a foot from the inner sides of the openings 4 and are slightly wider than said openings, the upper ends of said openings being below the 50 upper sides of said openings. The front faces of the walls are straight at at 30, for about half the height of the walls and otherwise are provided with rearwardly inclined or diverging surfaces 31. These vertical and 55 rearwardly inclined surfaces cause the air drawn in thru the openings 4 to be deflected upwardly and laterally and rearwardly as well, so that the air is deflected evenly throughout the forward ends of the chambers A and 60 is thus permitted to heat while passing upwardly towards the intake openings in the second stage. The baffle walls also prevent the direct flow of air to the rear ends of the chambers A.

65 Preferably the forward ends of the pipes

10 project beyond the forward ends of the third stages of the floor so as to be disposed beneath the second stages, whereby air will discharge from said pipes beneath the main intake openings. In order to prevent oil and dirt from dropping down into the pipes and to otherwise protect said pipes, a layer of fire-brick, as shown at 32, is laid upon the projecting ends of the pipes. The other ends of the pipes terminating, as shown in Fig. 4, 70 at a point spaced from the wall 3, are restricted, preferably by an element such as an angle iron piece 34, which partially covers said ends. This arrangement permits air to pass upwardly into the pipes at the restricted ends thereof and by having the pipes 75 slightly inclined so that only the restricted ends are lower than the opposite ends, a more effective circulation of air thru said pipes is provided for.

In operation of the furnace when the burners are ignited the flames will be projected substantially horizontally over the inclined stages of the floor of the furnace, such that the air to support combustion will be 90 drawn into the furnace thru the main intake openings and at the air ports otherwise provided in the floor. Air will enter the chambers A thru the openings 4 and when the fire-bricks of the floor become heated they 95 will heat the air beneath the floor and within said chambers A. By having the pipes inclined, air will pass thru into the said pipes at the lower ends thereof and said pipes will be heated due to their proximity to the floor. 100 The air thus passing thru the pipes will be heated before being discharged beneath the main air intake openings. Thus an effective quantity of heated air will be distributed at a point where it will be taken in thru the 105 main air intake openings and a thorough combustion will be provided for.

I claim:

1. An oil burning furnace including a burner, a floor having a downwardly inclined surface below the burner in front of the same, another surface contiguous with the first surface and having a plurality of air intake openings therein, an air chamber provided beneath said floor and a plurality of 110 pipes upon which said floor is mounted, which pipes extend lengthwise of said chamber and are open at both ends with certain ends disposed beneath said intake openings.

2. An oil burning furnace including a 120 burner, a floor having a downwardly inclined surface below the burner in front of the same, another surface contiguous with the first surface and having a plurality of air intake openings therein, an air chamber provided beneath said floor, and a plurality of 125 pipes upon which said floor is mounted, which pipes extend lengthwise of said chamber and are open at both ends with certain ends disposed beneath said intake openings, 130

said pipes being inclined so as to cause air to circulate from the lower to the upper end thereof.

3. An oil burning furnace including a burner, a floor having a downwardly inclined surface below the burner in front of the same, another surface contiguous with the first surface and having a plurality of air intake openings therein, an air chamber provided beneath said floor, a plurality of pipes upon which said floor is mounted, which pipes extend lengthwise of said chamber and are open at both ends with certain ends disposed beneath said intake openings, said pipes being inclined so as to cause air to circulate from the lower to the upper end thereof, said furnace having an air intake opening at one end of said chamber and a baffle member extending across said opening

arranged to intercept air entering the chamber thru said opening. 20

4. An oil burning furnace including furnace walls, a plurality of burners extending thru certain of said walls into the furnace, a floor for the furnace, means for supporting said floor above the bottom level of the furnace so as to provide an air chamber below the floor, said floor having inclined surfaces of varying inclination at points adjacent to, but below and in front of said burner, said floor having a plurality of air intake openings extending therethru at one of the inclined surfaces thereof, a partition extending lengthwise in said furnace and separating the burners and inclined surfaces 30 and intake openings from one another. 35

GEORGE C. ADAMS.
